IRON PILE

Enno Becker, Bremen, Germany, assignor to
 Vereinigte Stahlwerke Aktiengesellschaft, Dus-
 seldorf, Germany

Application June 8, 1933, Serial No. 674,948
 In Germany June 11, 1932

15 Claims. (Cl. 61—53)

This invention relates to iron piles and consists in an improvement of the arrangement claimed and described in my co-pending application Ser. No. 593,346, filed February 16th, 5
 5 1932, now U. S. Patent No. 2,010,254 of Aug. 6, 1935, in which the pile is provided with a laterally projecting shoe like thickening at such a distance from the pile point as to lie at the upper limit of the ground having carrying capacity 10 when the pile is driven.

According to the improvement forming the subject of the present invention not only that part of the pile which is arranged in the level of the ground having carrying capacity, but also 15 that part of the pile lying above thereof in the layers of the ground which have a less carrying capacity, is provided with a thickening.

Said upper thickening may be of the same or of greater dimensions yet lower strength than the lower thickened portion. The upper thickened portion can have less strength for the reason that the upper strata above the stable ground are not so compact as the lower layers. The length or height of the upper thickening is 20 optional. For instance, it can extend above the floor or it may alternatively terminate under the floor.

The upper thickening may consist for instance of light concrete with or without reinforcement 30 or another suitable material. If the upper thickening has greater dimensions than the lower thickened portion, the part of the upper thickened portion projecting beyond the lower one should be suitably protected while the pile is 35 driven in. Said protection can easily be obtained by extending the iron skin of the lower thickened portion in accordance with the dimensions of the upper thickening of the pile.

This type of pile with upper thickening has 40 the advantage to increase the reliability and bearing capacity of the pile to a considerable extent for the reason that hollow spaces in the upper portion of the pile, in so far as they are harmful, are eliminated and this portion can 45 thus take up also the share of frictional force of the top strata. Moreover, the upper thickening of the pile prevents expansion of the stable ground compressed by the lower thickening, as the hollow spaces in the upper pile portion have 50 been closed by the concrete. If the upper thickening is larger than the lower one the ground is moreover compressed while the pile is driven in, so that a further increasing of the bearing strength is obtained.

55 The utilization of concrete for the upper pile

thickening has moreover the advantage to give a protection for the surface of the pile covered with concrete against corroding. It is furthermore possible to make alike the moments of inertia of the pile with respect to the two main 5 axis thereof.

By way of example, the invention is illustrated in the accompanying drawing.

Figure 1 is a longitudinal section of a pile according to the invention.

Fig. 2 is a horizontal section of the pile on the line I—I.

Fig. 3 is a longitudinal section of a modified embodiment of the pile.

Fig. 4 is a cross-sectional view according to 15 the lines II—II of Fig. 3.

In the figures *a* represents the iron pile of I-shaped cross section, *b* the lower thickening and *c* the upper thickening. According to Fig. 1 the upper thickening is larger than the lower one 20 and it is protected at its bevelled middle portion by the element *e* of the iron skin *f* of the lower thickening. *d* are the iron insertions or reinforcing members for the concrete of the thickening. According to Fig. 3 the upper thickening 25 has the same dimensions as the lower thickening, but the iron insertions in the concrete have been omitted. In both cases the upper thickening extends to the ground.

The lower thickening *b* as illustrated on the 30 drawing, comprises a portion of the I-pile proper, sheet metal being secured, e. g. by welding, in place between the flanges of the I-pile and concrete being filled in the spaces or pockets formed by the sheet metal on the pile.

What I claim and desire to secure by Letters Patent in the United States is:

1. Iron pile intended to be rammed and possessing an I-shaped cross-section comprising a web portion and two flanges having a plurality 40 of concrete thickenings arranged between the flanges at both sides of the web portions, the lower one being arranged at such a distance from the lower end of the pile that in that part of the pile lying underneath said lower thickening long 45 grooves are formed which are open at their underside and closed at their upper side by the said thickening, said grooves being arranged in such a manner that the ground is firmly pressed into it upon the ramming in of the pile and is retained 50 therein by the said thickening, whereas each of the remaining thickenings immediately follows upon the lower one.

2. Iron pile intended to be rammed and possessing an I-shaped cross-section comprising a 55

- web-like portion and two flanges comprising two thickenings consisting of concrete and arranged between said flanges at both sides of said web-like portion and the lower one of said thickenings being arranged at such a distance from the lower end of the pile that in that part of the pile lying underneath said lower thickening long grooves are formed which are open at their underside and closed at their upper side by the 10 said thickening, said grooves being arranged in such a manner that the ground is firmly pressed into it upon the ramming in of the pile and is retained therein by the said thickening, whereas the upper thickening is of larger extension than 15 the lower one and immediately follows upon the latter, and comprising sheet iron parts in the form of a pocket arranged at the pile to embrace the outer surfaces of the lower thickening, and reinforcing iron insertions embedded into 20 the upper concrete thickening.
3. Iron pile intended to be rammed and possessing an I-shaped cross-section comprising a web-like portion and two flanges comprising a thickening consisting of concrete and provided 25 with sheet iron parts at its lower part, said thickening comprising two parts arranged at both sides of the web-like portion between the flanges and at such a distance from the lower end of the pile that in that part of the pile lying 30 underneath said thickening long grooves are formed which are open at their underside and closed at their upper side by the said thickening, said grooves being arranged in such a manner that the ground is firmly pressed into it 35 upon the ramming in of the pile and is retained therein by the said thickening, whereas the said sheet iron parts are arranged at the pile in such a manner as to embrace the lower part of the concrete thickening in the form of a 40 pocket.
4. A pile comprising an elongated iron member having an I-shaped cross-section and composed of a web portion and two flanges and concrete thickenings interposed between the flanges 45 of the iron member adjacent the lower end thereof.
5. A pile comprising an iron member having an I-shaped cross-section and composed of a web portion and two flanges and an iron skin disposed within the flanges adjacent the lower 50 end of the member and filled with concrete.
6. A pile comprising an iron member having an I-shaped cross-section and composed of a web portion and two flanges and metallic members secured within the flanges adjacent the lower end of the member and extending beyond the outer edges of the flanges and defining 55 upwardly open pockets, said pockets being filled with concrete.
- 60 7. A pile comprising an iron member having an I-shaped cross-section and composed of a web portion and two flanges and metallic members securing within the flanges adjacent the lower end of the member and defining upwardly open pockets, said pockets being filled with concrete.
- 65 8. A pile comprising an iron member having an I-shaped cross-section and composed of a web portion and two flanges and metallic members secured within the flanges adjacent the lower end of the member, said metallic members being fast to the web at their bottoms but spaced from the web at their tops thus forming

upwardly open pockets, said pockets being filled with concrete.

9. A pile comprising an iron member having an I-shaped cross-section and composed of a web portion and two flanges and metallic members secured within the flanges adjacent the lower end of the member, said metallic members being fast to the web at their bottoms but spaced from the web at their tops and outwardly flared thus forming upwardly open pockets, said 10 pockets being filled with concrete.

10. A pile comprising an iron member having an I-shaped cross-section and composed of a web portion and two flanges and metallic members secured within the flanges adjacent the 15 lower end of the member, said metallic members being fast to the web at their bottoms but spaced from the web at their tops, and the space between the metallic members and the web being filled with concrete. 20

11. A pile comprising an iron member having an I-shaped cross-section and composed of a web portion and two flanges and metallic members secured within the flanges adjacent the lower end of the member, said metallic members being fast to the web at their bottoms but spaced from the web at their tops and outwardly flared, the space between the metallic members and the web being filled with concrete and the space between the flanges above the 30 metallic members being filled with concrete extending to the outer edge of the flared portions of the metallic members. 25

12. A pile comprising an iron member having an I-shaped cross-section and composed of a web portion and two flanges and metallic members secured within the flanges adjacent the lower end of the member, said metallic members being fast to the web at their bottoms but spaced from the web at their tops and outwardly flared, the space between the metallic members and the web being filled with concrete and the space between the flanges above the metallic members being filled with reinforced concrete extending to the outer edge of the 40 flared portions of the metallic members. 45

13. A pile comprising an iron member having an I-shaped cross-section and composed of a web portion and two flanges and an iron skin disposed within the flanges adjacent the lower 50 end of the member and filled with concrete, said iron skin being outwardly flanged at its top and the space between the flanges of the iron member above the iron skin being filled with concrete extending past the flanges of the iron 55 member to the outer edge of the flange of the iron skin.

14. A pile comprising an elongated iron member composed of a web and two flanges, a concrete thickening interposed between the flanges of the iron member adjacent to the lower end thereof and a second concrete thickening above and of greater thickness than the first mentioned thickening. 60

15. A pile comprising an elongated iron member composed of a web and two flanges, a concrete thickening interposed between the flanges of the iron member adjacent to the lower end thereof and a second reinforced concrete thickening above and of greater thickness than the 70 first mentioned thickening.

ENNO BECKER.
